Des. 1678

Henry and Alfred S. Knobell of Buffalo, N.Y.
Letter Patent No 1678 - Dated Dec 9, 1862.

The schedule referred to in these Letters Patent and making part of the same

To all whom it may concern:

Be it known that we Henry S. Knobell and Alfred S. Knobell of the City of Buffalo, County of Erie, and State of New York, have invented or produced a new and original design for Cooking Stoves called the Advance, and we do hereby declare that the following is a full and exact description of the same, reference being had to the accompanying Photograph and the letters of reference made thereon,

Figure 1. is a perspective view of the stove. Letter A the top plate. D. D. the front of the stove H. H. the front doors E. the front bottom or fire hearth. F. the side & the end or fire door, B one of the oven sides both being the same. C one of the oven doors both being the same. G the oven top, what we claim as our invention or production and desire to secure by letters patent is the general design or configuration represented in the accompanying Photographs.
